(57) **CLAIM**

The ornamental design for an ethernet bridge datacom plug adapter, as shown and described.

DESCRIPTION

FIG. 1 is a front perspective view of the invention.

FIG. 2 is a rear perspective view of the invention.

FIG. 3 is a top perspective view of the invention.

FIG. 4 is a bottom perspective view of the invention.

FIG. 5 is a right side perspective view of the invention.

FIG. 6 is a front plan view of the invention; and,

FIG. 7 is a rear plan view of the invention.
